BUILDING

Louis Petrovitch, Neuilly-sur-Seine, France

Application April 14, 1932, Serial No. 605,303
In France December 22, 1928

4 Claims. (Cl. 98—29)

This invention has for its object improvements in or relating to buildings.

One of the drawbacks of present buildings lies in the fact that no means is provided to remove the foul air from the interior thereof, or, if such means be supplied, the exchange from the outer air to the inside air usually results in a substitution of outer foul air for inner foul air.

It has also been found that ventilation through windows alone is totally inadequate.

Lack of proper ventilation will necessarily result in undermining the health of the inmates of buildings wherein a proper supply of fresh and pure air is not forthcoming.

It is equally important that proper and sufficient natural light be supplied to such buildings.

This invention aims at taking advantage of air currents, whatever be the direction of the wind, to provide ventilation and ensuing sanitation and health. It further aims at so arranging and disposing a building that full advantage of normal and full light is had in all parts of the building.

Broadly stated, this invention contemplates a modern building characterized by the fact that it comprises a central or intermediate part, a plurality of wings each with one or more floors, arranged about the said part, said wings being rendered independent from one another at the sides by empty spaces obtaining the whole height up.

This arrangement constitutes an improvement over the one described in my French Patent No. 679,826 of 1928.

In the drawings:

Figure 1 is a diagrammatic showing, in plan view, of a building designed in accordance with my invention, with indication of the wind direction;

Figure 2 is a view similar to Figure 1, the direction of the wind being changed;

Figure 3 is a view similar to Figure 1, with a further change in the direction of the wind with respect to the building;

Figure 3' is a diagrammatic plan view showing the angle between the face of one building wing and the central axis of the adjacent wing;

Figure 4 is a perspective view of a building further embodying the instant invention;

Figure 5 is a plan view of the same;

Figure 6 is a perspective view;

Figure 7 is a detail view illustrating the ventiling device connecting the rooms of an apartment; and,

Figure 8 is a plan view showing a modification.

Figures 1, 2 and 3 illustrate the operation en-

sured by the arrangement the broad characteristics of which have just been set forth.

If the wind comes in the direction indicated by the arrow 3 (Figure 1) into the empty part comprised between the two wings 15, 15', said wind is divided by the intermediate part 17, penetrates into the convergent passages 18 which run through the wings or the said intermediate part, encounters there a section more and more narrowed down and, by compression, its velocity towards divergent passages 19 is increased. It passes in front of the apertures 20, wherein to open the ducts in communication with the rooms to be ventilated, produces an energetic depression, then passes through the divergent passages 19, carrying with it the foul air and flows out, crossing the empty spaces 21, producing a depression in front of the foul air outlets from the wing 15', the passage 19' in this wing being, on this account, divergent on the two sides of the wing.

On the other hand, a portion of the wind arriving as per the arrows 3' is deflected on the outer curved part of the wings 15 and 15' and, passing in front of the empty spaces 21, accelerates the foul air draught in the wings 15, 15' and 15''.

In Figure 2, the wind has been supposed to arrive in the direction indicated by the arrow 3. On the one hand, it penetrates into the empty part 16 comprised between the wings 15, 15'; it passes through the convergent passages 16 and divergent passages 19 and, on the other hand, it is deflected on the outer curved surface of the wings, thereby causing, through depression, a suction within the three wings.

As shown by Figure 3, the wind arrives normally on to a wing (arrow 3); it is deflected on the curved surface of wings 15, but, on account of the distance it has to travel and of its very pressure, it strikes the adjacent surface of the wing and slips outwards; this outward motion is obtained owing to the fact that the wall surface forms, an angle α' of over 90° with the axis of the wing, as shown in Figure 3.

A zone of depression is thus produced in the empty spaces 16, 16', 16'', which depression causes a suction of the foul air contained inside the wings.

It should be noted that, in the contrary case, that is to say if the angle α' above referred to was under 90° , the wind would get directed towards the central or intermediate part 17, bringing about a down-blow down apertures 20' through the conduits 18 which would be both convergent.

It should be remarked, on the other hand, that the ventilation of the building is also ensured

by the temperature differences which always exist between the empty parts 21, 21', 21'' and which bring about, in front of the apertures 20, an action which is similar to that of the wind.

5 As a matter of fact two masses of air at different temperatures tending to balance one another will make exchanges through the passages and keep them active.

10 From the foregoing it will be seen that natural ventilation will, during summer, permit of the rooms inside the wings being cooled in combination or not with cooling or filtering devices arranged in front of the air intake.

15 Likewise, during winter, the arrangement will permit of a predetermined temperature being kept up by causing air to pass through heating surfaces or other devices such as, for instance, radiators. In this manner both the heating and the airing can be simultaneously taken care of.

20 Lastly, I will point out that the air circulation system hereinabove set forth may be combined, in certain cases, with mechanical or other contrivances (ventilators, fans, thermostats, etc.) suitably arranged.

25 I will now indicate, as an example, a method of constructing a building in accordance with my invention.

30 Referring first to Figures 4, 5 and 6, the building comprises a central part 17 from which radiate three symmetrical wings 15, 15', 15'' having any number of superimposed floors or stories and rendered independent from one another laterally by empty spaces 21, 21', 21'' converging towards the said central part 17 in the conditions and for 35 the purpose hereinbefore specified. This arrangement gives for each wing, as is clearly shown by the drawings and as has already been stated, three fronts perfectly exposed to the sun.

35 In the central part 17 are the furnace chimney 40 24, a staircase 25, elevators and hoists 26, piping 27 for water, gases, electricity and refuse to sewer flushing.

40 The forced natural ventilation or airing of the rooms in the building may be performed in a variety of ways, all of them based, however, on the 45 above defined principle.

45 In the case considered, there are provided at all suitable points in the ceiling 28 of each room one or several apertures 29 connecting the said 50 room either through suitable channels such as 30

(Figure 6) located between the ceilings and the floors 31, or through the clearance existing between those ceilings and floors, with convergent-divergent passages 18-19. These passages are intended to discharge, through an aperture 20 5 with which their middle part is provided, the foul air coming from inside the rooms, either through channels 30 or through the clearance between the ceilings 28 and the floors 31 of the story next above, as hereinbefore indicated.

10 The said passages may be formed either within the thickness of the ceilings or between those ceilings and suitable dummy ceilings 32 provided for this purpose (Figure 7).

15 The operation of the system having been set forth in reference to Figures 21, 22 and 23, I will dwell no more on the point.

20 All the explanations hereinabove given hold good for the method of performance illustrated by Figure 28.

25 What I claim is:—

1. A building structure comprising a central portion and a plurality of wings disposed about said central portion and connected thereto, said wings providing empty spaces between each other, 25 and said spaces being interconnected, at points along the height of the building structure, by means of convergent-divergent passages, whereby an unimpeded flow of air between the wings is permitted through the said passages, and openings between the interior of each of said wings and said passages, whereby evacuation of the foul air within the interior of the wings is permitted through the said passages.

30 2. A building according to claim 1, in which the wings are designed so that the axis of each one of these wings and the wall of the adjacent wing form an angle of preferably over 90°.

35 3. A building according to claim 1, in which the passages connecting the empty spaces comprised between the wings are arranged within the thickness of the main floor; openings terminating on convenient points of said passages, for evacuating the foul air.

40 4. A building according to claim 1, in which the passages connecting the empty spaces comprised between the wings are arranged underneath the ceiling.

45 LOUIS PETROVITCH. 50
